his ATTORNEY

UNITED STATES PATENT OFFICE.

SAMUEL Z. HALL, OF LITTLE ROCK, ARKANSAS.

COTTON-GIN RIB.

SPECIFICATION forming part of Letters Patent No. 239,298, dated March 22, 1881.

Application filed July 24, 1880. (Model.)

To all whom it may concern:

Be it known that I, SAMUEL Z. HALL, of Little Rock, in the county of Pulaski and State of Arkansas, have invented a new and valuable Improvement in Cotton-Gin Ribs; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a side view of my improved gin, and Fig. 2 is a section thereof.

This invention has relation to improvements in cotton-gins; and it consists in the construction and novel arrangement of parts, as hereinafter shown and described.

In gins heretofore constructed one of the great obstacles encountered is that, owing to the construction of the ribs, cove, and roll-box, too much friction is produced in keeping the roll of seed-cotton in contact with the saws and a corresponding expenditure of power uselessly caused, the roll being only held in front of the saws by its fullness and compactness. The roll therefore rubs forcibly against the ribs, and twice as much power is required to run the gin as would be required to merely strip the lint from the seed were said unnecessary friction done away with. This is effectually accomplished by means of the rib hereinafter described, wherein the frictional surface on the rib is reduced from about eight to ten inches to three-fourths of an inch.

In the annexed drawings, the letter A designates my improved rib, the same being of slightly serpentine form in elevation and of triangular form in cross-section. It is provided at its upper end with a tang, *a*, and at its lower end with a flattened extension, *b*, by means of which it is attached to the gin-frame by means of suitable screws extending through suitable perforations in the tang and extension and driven into the said frame. The tang *a* forms, with the body of the rib, a shoulder, *c*, and with the first curve, *d*, of the rib an angle, *d'*. This curve *d* is described from the point *d'*, which is about one and three-quarters inch from the cove or arched roof of the roll-box B, with a radius of four and one-quarter inches, this curve being flat, comparatively, and terminating at a point about two and one-

sixteenth inches from the point *d'* aforesaid, lettered *e* in the drawings. At this point commences a sharper curve, *f*, described with a radius of one inch, and terminating at the point *i*, where the saw intersects the rib—say about three-quarters of an inch from the point *e* aforesaid. From this point *i* to the point *d'* the ribs are in that portion of the gin denominated as the "roll-box," and the mass of seed-cotton is rolled around in said box by the action of the saws thereon, and new surfaces subjected to the action of the saws. When the roll enters the curved portion *f* of the ribs it is compressed thereby, and is held forcibly against the saws, which strip off the lint, at the point *i*, from the seed; but when the said roll enters the curved space *d* of the ribs it has more room, and consequently expands and becomes less compact. Thus it exercises little or no friction on the portion *d* of the ribs, appreciable friction occurring only in the curve *f* thereof, where it is requisite to hold the roll against the saws. The roll thus turns rapidly, and the ginning is done quickly and thoroughly.

The portions *d f* of the rib, instead of being curved, as described, may be made angular, the angle at the part *d* being much more obtuse than that at the part *f*, with an approximately good result; but I prefer to use the curved surfaces above set forth.

I do not wish to be understood as confining myself to the precise dimensions and measurements above set forth, the gist of my invention being in the curved surfaces *d f* formed in the face of the rib described, the former with a longer radius than the latter.

What I claim as new, and desire to secure by Letters Patent, is—

The cotton-gin rib constructed with the two concave curves *d f*, the latter being below the former, and commencing where the saw intersects the upper part of the rib, and having a shorter radius of curvature than the former, the two meeting by a projecting point, *e*, as shown and described.

In testimony that I claim the above I have hereunto subscribed my name in the presence of two witnesses.

SAMUEL Z. HALL.

Witnesses:

CHARLES H. TRIPP,
EUGENE M. WHEELER.
